UNITED STATES PATENT OFFICE.

HENRY A. HOWARD, OF LLOYDMINSTER, SASKATCHEWAN, CANADA.

DRIVING MECHANISM FOR TRACTION-ENGINES.

1,012,552.

Specification of Letters Patent. Patented Dec. 19, 1911.

Application filed April 15, 1911. Serial No. 621,236.

To all whom it may concern:

Be it known that I, HENRY A. HOWARD, a subject of the King of Great Britain, residing at Lloydminster, in the Province of 5 Saskatchewan, Canada, have invented certain new and useful Improvements in Driving Mechanism for Traction-Engines; and I do hereby declare the following to be a full, clear, and exact description of the invention, such as will enable others skilled in 10 the art to which it appertains to make and use the same.

My invention has for its particular object the provision of an improved driving mechanism for traction engines and similar machines, and to this end the invention consists of the novel devices and combinations of devices hereinafter described and defined in the claims.

20 In the accompanying drawings which illustrate the invention, like characters indicate like parts throughout the several views.

Referring to the drawings, Figure 1 is a fragmentary plan view showing the improved driving mechanism applied to a frame and rear axle of a traction engine; Fig. 2 is a side elevation of the mechanism shown in Fig. 1, some of the parts being sectioned; Fig. 3 is a detail in section taken 30 approximately on the line $x^3 x^3$ of Fig. 2; Fig. 4 is a view in side elevation with some parts broken away showing the constructions of the differential or compensating gear used in the improved driving mechanism; Fig. 5 is a section taken on the irregular line $x^5 x^6$ of Fig. 4; Fig. 6 is an enlarged view corresponding to Fig. 3; Fig. 7 is a fragmentary view in side elevation showing on a larger scale than in Fig. 2 the 40 ratchet mechanism of the improved drive; Fig. 8 is a detail in section on the line $x^8 x^9$ of Fig. 7, some parts being removed; and Fig. 9 is a fragmentary view in section on the line $x^9 x^9$ of Fig. 8.

45 The numeral 1 indicates a portion of the framework, the numeral 2 the divided rear axle, the numeral 3 the rear or traction wheels, and the numeral 4 the engine driven shaft of the traction engine, the said shaft being mounted in suitable bearings in the frame 1, and one of the said bearings being indicated at 5 in Figs. 1 and 2.

The compensating gear, here employed, in its action is like that of one of the well 55 known forms of compensating gears, and it comprises a pair of bevel gears 6, one keyed

to each of the sections of the rear axle 2 near the inner ends thereof. The driving member of the compensating gear is, however of novel form and it comprises a heavy rim 7, 60 spokes 8, and a hub 9. The hub 9 is loosely journaled on the abutting ends of the axle sections 2 and the spokes 8 extend outward between the two beveled gears 6. Certain of the spokes 8 carry bevel pinions 10 suitably journaled thereto and meshing with the teeth of both of the bevel gears 6. The rim 7 of the driving member or wheel is provided at both edges with external ratchet teeth 11 and with internal ratchet teeth 12. 70 The internal and external ratchet teeth are reversely beveled so that they coöperate with driving dogs to rotate the said wheel or driving member in reverse directions.

Immediately pivoted on the hub of each 75 gear 6 is an oscillatory driving lever 13. Each lever 13 carries a double ended reversible driving pawl or dog 14 which is pivoted thereto at 15. When the outer ends of the driving dogs 14 are set for coöperation with 80 the outer ratchet teeth of the wheel member 7, the said wheel, and hence, the rear axle 2 and traction wheels 3 will be rotated in a direction to drive the machine forward; but when the inner ends of the said driving dogs 85 are set for coöperation with the inner ratchet teeth 12, the said traction wheels will be reversely driven, or in other words, will cause the machine or traction engine to move backward.

90 For coöperation with each dog 14 there is a pronged shipper lever 16 pivoted to a notched segmental latch plate 17 carried by a coöoperating lever 13. These levers 16 are provided with latches 18 that are engageable 95 with the notches of the coöoperating latch segments 17 to hold the said levers in either of two extreme positions. The prongs of the levers 16 are provided with light springs 19 that coöperate with the dogs 14 to yieldingly hold the same, in the one instance, for engagement with the outer, and in the other instance for engagement with the inner ratchet teeth of the wheel rim 7.

100 The numeral 20 indicates a pair of segmental heads provided each with a pair of diverging arms 21 the ends of which are pivoted to the ends of the coöoperating levers 13 so that the said heads 20 are free for lateral movements. In their segmental faces, 110 the heads 20 are provided with long openings 22 and on each side of said openings

with toothed racks 23 and 24. The extremities of the slots 22 beyond the rack teeth 23 and 24 are approximately semicircular. And on the outer faces adjacent to the extremities of the racks the said heads are provided with lugs or teeth 25 and 26 and, at the extreme ends of the slots, they are further provided with teeth or lugs 27. Also, each rack head is provided with a longitudinally and vertically extended inwardly projecting segmental guide flange 28. The guide flange 28 of each head coöperates with the end portion 29 of a guide arm or bracket 30, both of which guide arms are rigidly secured 15 to the framework 1.

The driving shaft 4 extends through the slots 22 of both of the rack heads 20 and it is provided with two pinions 31. One of these pinions 31 coöperates with the teeth of 20 one of the rack heads and the other coöperates with the teeth of the other rack head. Secured to the driving shaft 4 adjacent to each pinion 31 is a segmental shifting flange 32 provided with an intermediate notch 33. 25 When the driving shaft 4 is rotated the pinions 31 will be engaged alternately with the coöperating rack teeth 23 and 24 of the respective heads 20, and thus the said heads 20 and the levers and arms connected thereto 30 will be oscillated but the arrangement is such that the two heads 20 will be simultaneously oscillated in reverse directions so that the coöperating driving dogs will be alternately thrown into action on the toothed 35 wheel rim 7 and continuous driving force thereby applied to the said driving wheel and through the latter and compensating gear the rear axle and traction wheels.

The manner in which the racks 23 and 24 are alternately engaged with the coöperating pinions 31 is as follows: When one of the rack heads 20 reaches its extreme uppermost or lowermost position, the coöperating pinion will be thrown out of engagement with the 40 one rack and into the other by the engagement of the notch 33 of the shifting head 32 with one or the other of the end lugs 27 of the said rack head. The said rack head will be given a rigid lateral movement necessary 45 to shift the one rack head out of engagement with the said pinion and the other rack into engagement with the said pinion. The lugs 25 and 26 coöperate with the extremities of the shifting head 32 after the manner 50 of a segmental gear and hold the said segmental heads against vertical movement while the racks are being shifted. When the rack head is moved upward by engagement of one of the lugs with the coöperating pinion, the guide flange 28 of the said head will 55 pass on one side of the end 29 of the coöperating guide bracket 30 and when the said rack head is moved downward by engagement of the other rack with the said pinion, 60 the said flange 28 will be so shifted by lat-

eral movement of said head that it will pass downward on the other side of the said end 29. In this way, the said elements 28 and 29 serve to maintain engagement of the proper rack with the pinion while the rack 70 head is being moved from one extreme position to another.

Through the driving mechanism described, a relatively slow but relatively very great driving force is transmitted from the 75 driving shaft to the traction wheels and the compensating gear takes care of the differential movements of the traction wheels in turning curves:

What I claim is:

1. In a driving mechanism, the combination with a driving shaft and a driven shaft, of a wheel connected to said driven shaft, a vibratory lever, pawl and ratchet devices connecting said lever and said wheel, a rack 85 head having an arm pivoted to said lever and provided in its outer face with laterally spaced racks, a pinion on said driving shaft, and means for shifting said rack head to alternately engage the racks thereof with 90 said pinion.

2. In a driving mechanism, the combination with a driving shaft and a driven shaft, of a wheel connected to said driven shaft, an oscillatory lever, pawl and ratchet devices connecting said wheel and said lever, a segmental rack head provided with an arm pivoted to said lever for lateral movements and having on its segmental face laterally spaced racks, a pinion carried by said driving shaft, and means carried by said driving shaft and said rack head, for shifting the latter at the extremities of its movement to thereby alternately engage the said racks with said pinion.

3. In a driving mechanism, the combination with a driving shaft and a driven shaft, of a wheel connected to said driven shaft, oscillatory levers, pawl and ratchet devices connecting said wheel and said levers, segmental rack heads provided with arms pivotally connected to respective levers for lateral movements, the said rack heads having laterally spaced racks, pinions carried by said driving shaft for coöperation with the rack teeth of each rack head, and coöperating means carried by said shaft and by said rack heads for alternately shifting the racks of said heads into and out of mesh with the coöperating pinions in reverse order.

4. In a driving mechanism, the combination with a divided shaft, of a compensating gear connected to the section of said shaft and including a driving wheel having a rim with internal and external ratchet teeth, an oscillatory lever adjacent to said driving wheel, means for oscillating said lever, a reversible driving dog carried by said lever for coöperation, at will, with either the internal or external ratchet teeth of said driv-

ing wheel, and means for setting said dog, at will, in either of its two operative positions.

5. In a driving mechanism, the combination with a driving shaft and a driven shaft, of a driving wheel connected to said driven shaft and having reversely internal and external acting distinct sets of ratchet teeth, a lever provided with a reversible driving dog 10 for action on either set of the ratchet teeth of said driving wheel, arms pivotally attached to said lever, and means carried by said driving shaft and operative on said arms to oscillate the same both vertically 15 and horizontally, substantially as described.

6. The combination with a driving shaft and a driven shaft, of a driving wheel on said driving shaft, a lever, pawl and ratchet, devices connecting said wheel and said lever,

a segmental rack head having an arm pivotally connected to said lever for limited lateral movements, and provided in its segmental face with laterally spaced racks and with shifting lugs at the extremities of said racks, a pinion carried by said driving shaft, 25 for coöperation with said racks, and a notched segmental head carried by said driving shaft and coöperating with the shifting lugs of said head, to move the said head laterally at the limits of its movement and thereby alternately engage the said racks 30 with said pinion.

In testimony whereof I affix my signature in presence of two witnesses.

HENRY A. HOWARD.
